W. H. STONE

COMBINATION NUT LOCK AND PISTON ROD LUBRICATOR

Filed Sept. 4, 1920

Patented Aug. 21, 1923.

1,465,495

UNITED STATES PATENT OFFICE.

WILLIAM H. STONE, OF KANSAS CITY, MISSOURI.

COMBINATION NUT LOCK AND PISTON-ROD LUBRICATOR.

Application filed September 4, 1920. Serial No. 408,238.

To all whom it may concern:

Be it known that I, WILLIAM H. STONE, a citizen of the United States, residing at Kansas City, in the county of Jackson and

5 State of Missouri, have invented certain new and useful Improvements in Combination Nut Lock and Piston-Rod Lubricators, of which the following is a specification.

My invention relates to a combination nut 10 lock and piston rod lubricator and while it may be employed to advantage for locking the stuffing box nuts and lubricating the piston rods of various machines it is more particularly adapted for use on air pumps such 15 as are employed on railway locomotives for supplying the air brake system with compressed air.

The device is so constructed that it can be readily installed or removed without taking apart any of the mechanism on which it 20 is employed and when in use not only locks the stuffing box nuts in position and lubricates the piston rod, but also protects the latter from dust, grit and other foreign matter likely to cause undue wear and leakage 25 of air and steam around said piston rod.

In order that the invention may be fully understood, reference will now be had to the accompanying drawing, in which:

30 Fig. 1 is an elevation of a portion of an air compressor, with the device in section thereon.

Fig. 2 is a plan view of the device.

Fig. 3 is an elevation of the device in 35 closed position.

Fig. 4 is an elevation of the device in open position.

Fig. 5 is an irregular fragmentary section on line V—V of Fig. 1.

40 In carrying out the invention, I employ a shell 2, made in two sections 4 and 6, connected by hinges 8 and held in closed position by a staple 10 and a hook 12. Said hook 12 is pivotally mounted upon a hasp 45 14 secured by suitable fastening means such as rivets 16 to the opposite side of the shell from that containing the staple 10. The ends of the shell 10 are cut away at intervals as indicated at 18, to provide fingers 20, 50 for a purpose which will hereinafter appear.

The shell sections 4 and 6 are provided with segmental screen sections 22 spaced from the interior of the shell by longitudinal spacing members 24 and segmental spacing members 26 secured to the interior of the shell by pins 28. The pins 28 are held in

place by integral heads 30 and washers 32, which latter are pressed over the inner ends of said pins 28 and against the interior of the screen sections 22, thus reliably holding 60 the same against the spacing members 24 and 26.

Dust proof lubricant chambers 36 are formed between the interior of the shell 2 and the screen segments 22 for holding 65 grease or other heavy lubricant, adapted to saturate wicking 38 or other absorbent material held in place against the interior of the screen sections 22 by the pins 28.

The air compressor shown in the drawing 70 is of the usual type embodying a steam cylinder A and an air cylinder B having piston heads C and D, respectively, connected by a piston rod E. The adjacent cylinder heads F and G are united by a segmental member H and have the usual stuffing boxes I and J, equipped with nuts K and L, respectively.

In practice the shell 2 is opened and placed 75 around the piston rod E and then secured in closed position by the staple 10 and the hook 12. In placing the shell 2 in position the fingers 20 are engaged in the recesses between the peripheral lugs on the nuts K and L and thus lock the same against unscrewing. When steam is admitted to the cylinder A to reciprocate the piston heads C and D and the rod E, the latter becomes 80 warm and softens the grease in the lubricant chambers 36, causing a portion of said grease to flow through the perforations in the screens 22 and saturate the wicking 38, which in turn lubricates the piston rod E and protects it and the stuffing boxes I and J from undue wear. Grit, dust and other 85 foreign matter likely to score or otherwise injure the piston rod E is excluded by the shell 2 and the stuffing boxes I and J. The device can be readily removed when the 90 grease and wicking are to be renewed.

100 While I have shown and described the preferred form of the invention, I reserve the right to make such changes as properly fall within the spirit and scope of the claims.

Having thus described my invention, what I claim and desire to secure by Letters Patent, is:

1. A device of the character described consisting of a vertically disposed cylindrical shell adapted to be opened for placement around a piston rod, means for securing 110 said shell in closed position around the pis-

ton rod, a vertically-disposed cylindrical screen fixed within said shell and arranged to open and close therewith, said screen being spaced from the shell to leave a dust-proof chamber for a lubricant adapted to pass through the screen and lubricate the piston rod, and means projecting inwardly from the device for holding absorbent material between the screen and the piston rod 10 to distribute the lubricant over the latter.

2. A device of the character described consisting of a vertically disposed cylindrical shell made in sections, hinges connecting said sections so that the shell may be opened

and closed, a vertically-disposed cylindrical screen fixed within the shell to open and close therewith; said screen being spaced from the shell to leave a dust proof lubricant chamber, means for securing the shell in closed position, and integral extensions at 15 the upper and lower ends of the shell, for the purpose described.

In testimony whereof I affix my signature, in the presence of two witnesses.

WILLIAM H. STONE.

Witnesses:

F. G. FISCHER,

L. J. FISCHER.
